Inventor:
Robert W. Joy by
J. H. Gibbs Atty.

UNITED STATES PATENT OFFICE.

ROBERT W. JOY, OF BROOKLYN, NEW YORK, ASSIGNOR TO AMERICAN CAR AND FOUNDRY COMPANY, OF NEW YORK, N. Y., A CORPORATION OF NEW JERSEY.

RAILWAY-CAR.

1,336,436.

Specification of Letters Patent. Patented Apr. 13, 1920.

Application filed May 5, 1919. Serial No. 294,663.

To all whom it may concern:

Be it known that I, ROBERT W. JOY, residing at Brooklyn, Kings county, State of New York, and being a citizen of the United States, have invented certain new and useful Improvements in Railway-Cars, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

In said drawings:

Figure 1 is a central vertical section through my improved pedestal and journal box, shown attached to the side sill of an industrial car;

Fig. 2 is a view, partly in front elevation and partly in section; and

Fig. 3 is a horizontal section through the pedestal, the journal box being shown partly in plan and partly in section.

It is to be understood that the invention is not limited to the exact details of construction shown and described, as it is obvious that various modifications thereof within the scope of the claims will occur to persons skilled in the art.

My invention relates to journal boxes and pedestals for railway cars and is adapted especially for small cars such as cane cars and industrial cars and it is an object of my invention to provide a pedestal that will shield the journal box from rain and dirt and from material falling from the car and will also serve to keep the journal box lid locked in place so that the brass journal bearing cannot be removed unless the pedestal and car are elevated.

Referring to the drawings, 1 designates the pedestal which is preferably formed as a casting having side members 2 joined by a projecting top member 3 and a web 4 joining the front edges of the side members and which web is provided with openings 5 and 6, which latter is formed of sufficient area to permit the lid to swing outwardly when desired, and the parts are in proper position to permit it, for replacement of the

brass journal bearing. The top member 3 is provided with a flange 7 which is secured to a framing member of the car, in the present instance the car sill 8, by rivets 9 and the top member 3 and flange 11 of the car side sill 8 are joined by rivets 10. At the bottom of each side member 2 is an outwardly extending flange 12 provided with a bolt opening 13 and each side member 2 is provided at its rear edge with an outwardly extending reinforcing flange 14 which is journaled to the projecting top member 3 and to the corresponding flange 12.

The side members 2 are each provided with an inwardly extending lip 2^a to serve as guides and retaining stops for the lugs 22 hereinafter referred to.

The journal box 15 consists preferably, though not necessarily, of a casting having a top 16, sides 17 and bottom 18, a channel 19 being provided at the inner end for the usual dust guard (not shown) and having the usual opening for an axle 27. The front of the box is closed by a hinged lid 23 which is provided with an oil opening 26 adapted to be closed by a pivoted cover 24 secured to the lid 23 by a rivet 25. A pin 21 passing through the lugs 20 extending from the bottom 18 of the journal box 15 and intermediate lug 22 extending from the lid 23 secures the lid 23 to the box 15.

In assembling the journal box and pedestal, the box is placed on the axle 27, a brass journal bearing 34 being placed between the journal box and the axle, the lid 23 is closed and the journal box is entered between the sides 2 at the bottom of the pedestal. The pedestal is then lowered until the spring 28, placed between the journal box top 16 and the under side of the pedestal top member 3, transmits the load of the car body to the journal box. To retain the spring 28 in position, central annular projections 29 and 30 are provided on the top 16 of the journal box and the under side of top member 3 of the pedestal, respectively. A tie bar 31, secured to the flanges 12 by bolts 32, joins the pedestals on each side of the car and, passing beneath the opening between the sides 2 of each pedestal, prevents the withdrawal of the journal box.

When the journal box is in place, the lugs 22 of the lid and the ends of the pin 21 are shielded by the lower flange portions 2^a of the pedestal sides 2 so that the pin 21

cannot be withdrawn and the upper end of lid 23 is in back of the web 4 so that the journal box lid 23 cannot be tilted or the pin 21 withdrawn and the lid 23 swung outwardly without elevating the pedestal and car body thus preventing the ready removal of the brass journal bearings 34 by unauthorized persons.

The lid 23 is provided, on its inner face, with a projection 33 adapted at times to be engaged by the end of the axle 27 so that the lid 23, when held in place by the pin 21 and web 4 of the pedestal, serves as a renewable thrust plate and is adapted to take the end thrust of the axle 27.

The journal box and spring being behind the sides 2 and web 4 are protected by the pedestal from material falling from the car and from blows from obstructions along side the track.

What I claim is:

1. The combination of a pedestal, a journal box and a lid for said journal box engaged by said pedestal.
2. The combination of a pedestal and a journal box having a lid held closed by said pedestal.
3. The combination of a pedestal, a journal box having a lid and means on said pedestal engaging said lid.
4. The combination with a pedestal having a web, of a journal box having a lid engaged by said web.
5. The combination with a pedestal having a web, of a journal box having a lid held closed by said web.
6. The combination with a pedestal, of a journal box having a thrust plate held in position by said pedestal.
7. The combination with a pedestal, of a journal box having a thrust plate and means on said pedestal holding said thrust plate in position.
8. The combination of a pedestal, a journal box, a lid for said journal box adapted to receive the end thrust of an axle and

means on said pedestal holding said lid in position against the end thrust of the axle.

9. The combination of a pedestal, a journal box, a lid for said journal box adapted to receive the end thrust of an axle and a web for the pedestal engaging said lid and holding it in position against the end thrust of the axle.

10. The combination of a pedestal, a journal box having a lid, a pin securing said lid to said journal box and means on said pedestal securing the pin in position.

11. The combination of a pedestal having side members, a journal box having a lid and a pin securing said lid to said journal box and held in position by the side members of the pedestal.

12. The combination of a pedestal having side members and a web, a journal box, a lid for said journal box engaged by said pedestal web and a pin securing said lid to said journal box and held in position by the pedestal side members.

13. The combination of a pedestal having side members and a web joining the side members, a journal box, a lid for said journal box adapted to receive the end thrust of an axle and held closed by said pedestal web and a pin joining said lid to said journal box and held in position by the pedestal side members.

14. The combination of a pedestal and a journal box having a lid held closed by said pedestal while said journal box is in its normal position in said pedestal.

15. The combination of a pedestal and a journal box having a lid secured to said box by said pedestal while said journal box is in its normal position in said pedestal.

In witness whereof I have hereunto set my hand in the presence of two witnesses.

ROBT. W. JOY.
